[54] MULTI-PRODUCT FUEL DISPENSER[75] Inventor: John A. Todd, Salisbury, Md.[73] Assignee: Dresser Industries, Inc., Dallas, Tex.[] Term: 14 Years[21] Appl. No.: 952,166[22] Filed: Oct. 17, 1978[51] Int. Cl. .... D15—02[52] U.S. Cl. .... D15/9.2[58] Field of Search D15/9.1, 9.2, 9.3;
222/25-28, 32-37, 75, 530[56] References Cited*U.S. PATENT DOCUMENTSD. 99,546 5/1936 Hudspeth D15/9.3
D. 194,433 1/1963 Chaffee D15/9.2
D. 237,822 11/1975 Gray ..... D15/9.2D. 237,823 11/1975 Gray D15/9.2
D. 244,563 5/1977 Taylor D15/9.1
D. 247,134 1/1978 Geisler D15/9.1
3,199,727 8/1965 Fromanowski ..... 222/32 X
3,797,703 3/1974 Yamawaki ..... 222/32 X*Primary Examiner*—Nelson C. Holtje*Attorney, Agent, or Firm*—Daniel Rubin[57] CLAIM

The ornamental design for a multi-product fuel dispenser, as shown and described.

DESCRIPTION

FIG. 1 is a front elevational view of a multi-product fuel dispenser showing my new design, the rear being a mirror image thereto;

FIG. 2 is a top plan view thereof;

FIG. 3 is a left end elevational view thereof, the right end being substantially similar thereto but without the projecting upper and lower housings.

U.S. Patent

Sep. 22, 1981

Des. 260,897

FIG. 1

FIG. 2

FIG. 3